(57) **CLAIM**

The ornamental design for a vehicle grill pattern, as shown and described.

DESCRIPTION

FIG. 1 is a schematic front view of vehicle grill pattern shown on a vehicle on a reduced scale;

FIG. 2 is perspective view of a portion of a vehicle grill pattern in accordance with the present invention;

FIG. 3 is a front view of a portion of a vehicle grill pattern in accordance with the present invention.

FIG. 4 is another perspective view of a portion of a vehicle grill pattern in accordance with the present invention; and,

FIG. 5 is a cross sectional view of a portion of a vehicle grill pattern taken along line 5—5 in FIG. 3.

The vehicle and grill portions shown in broken lines are for illustrative purposes only and form no part of the claimed design. The top, bottom and rear of the grill pattern form no part of the claimed design.
